IGNITION APPARATUS

Tullio Tognola, Sidney, and Whitfield C. Smith,
Oneonta, N. Y., assignors to Bendix Aviation
Corporation, New York, N. Y., a corporation of
Delaware

Application November 8, 1945, Serial No. 627,474

6 Claims. (Cl. 315—57)

1

This invention relates to ignition apparatus for internal combustion engines and more particularly to a unit which will be called a spark plug although its functions and structure are more complex than the primitive piece of electrical equipment which ordinarily goes by that name.

An object of the present invention is to mount a transformer coil in proximity to an engine. Another object of the invention is to assemble the high tension portions of an electrical ignition system within a small compass in proximity to the spark electrodes served thereby. Another object of the invention is to assemble as one unit an ignition coil, a condenser, an air gap, and the electrodes of a spark plug in order to simplify the wiring and ignition system of internal combustion engines operated from remote positions. A particular object of the invention is to employ a condenser and air gap in immediate association with the electrodes of a spark plug. Another object of the invention is to construct the sparking electrodes and the high tension current generating portions of an ignition system as complementary units that can be assembled easily and when so assembled constitute a complete, radio-shielded plug of unobjectionable size capable of being mounted upon an engine.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference characters refer to like parts throughout the several views,

Fig. 1 is a vertical sectional view through a spark plug constructed in accordance with the preferred principles of the invention; and

Fig. 2 is a circuit diagram illustrative of the principles of the invention.

In Fig. 1 a spark plug is provided with an electrode 10 which comprises the outer shell of the unit. This shell is composed of a cylindrical metal base member 11 exteriorly screw threaded, inwardly provided with a conical seat 12, and having a recess 13 which receives the annular electrode 10. The cylindrical base member has a shoulder 14 adapted to make sealing contact with the wall of an engine cylinder and has an

annular flange 15 upon which, in fully assembled relation, a tubular shell 16 is butt soldered. The outer abutting corners of members 15 and 16 may be reduced in order to form a groove 17 for the reception of solder such as silver solder. Welding can alternatively be employed for joining the portions 15 and 16 of the shell. An inner electrode 18 encircled by insulation 19 is mounted in the base member 11 by means of conical wedge 20 which conforms to the conical seat 12, and, being of relatively soft material such as copper, is capable of giving satisfactory support to the combined structure.

It is desired to mount the spark generating and regulating means in the closest proximity to the electrodes of the plug without mounting objects of objectionable bulk upon an engine. In order to attain this objective, the transformer windings, a condenser, and a gap cell are constructed as a unit to be mounted about the center electrode. In the drawing, the numeral 30 signifies a sleeve made of some satisfactory dielectric material such as a ceramic, the outer surface of which is provided with a helical groove 31 for the reception of the wires 32 of the primary coil of a transformer. The wire of this coil need not be insulated if the groove is deep enough, but in other cases it may be advisable to employ a wire having plastic insulation. Such wire is illustrated in the accompanying drawing at 32'. The sleeve 30 has a flange 33 of annular character at its lower end which is adapted to receive the flange 34 of a grounding ring 35 which is connected through the conical wedge 20 and the base member 11 to the metal of the motor. One end of the primary winding is secured and electrically connected to the grounding ring 35, at 36.

The grounding ring 35 projects inwardly beyond the wall of the sleeve 30 and serves as a support for a tube 41 of mica or other dielectric material upon which is wound the secondary windings 42, one end 46 of which is grounded and connected to one end of the primary winding 32 at point 36.

The mica tube 41 is preferably provided with a plurality of layers between which, at one end, the downturned ends of spring 43 are caught. This spring is electrically connected to the output end 45 of the secondary and has an offset 44 which serves to make firm contact with the end of the center electrode 18 so that discharges from the secondary will be conducted to the electrode and cause the ignition spark by leaping the gap between electrodes 18 and 10.

The structure as so far described may be assembled by winding a sufficient number of turns of mica to provide a support, winding or otherwise mounting the turns of the secondary coil upon the mica support, connecting an end thereof to the spring 43, inserting the secondary in the sleeve 30, and bringing the other end 46 thereof out through an opening provided for that purpose between the ring 35 and bushing 20. The ring 35 holds the secondary in place. The primary may now be wound upon the outside of the dielectric sleeve and when energized will generate currents of high potential in the secondary.

An air gap cell is electrically located between the condenser and the primary and serves, inter alia, the purpose of regulating the charge delivered thereto and of offsetting the effect of different air pressures existing at different heights. In the sleeve 30 is a partition 37 beyond which, toward its upper end, is a recess 38 which is adapted to receive the air gap cell, generally indicated by the numeral 50.

The air gap cell 50 comprises a glass cylinder 51 having metallic end pieces 52, 53 which are connected thereto by fusing the metal and glass together until a permanent joint is made. The fusing of the metal bases to the glass occurs under slight pressure when both are heated to red heat. The plate 52 carries the high side electrode 54 which may be made of cut nickel or the like, and which is preferably tipped with tungsten as indicated at 55. The low side electrode 56 is similarly constituted and is also provided with a tungsten tip 57. The tungsten tips need not be of great size, their general purpose being to prevent the disintegration of the electrodes under the effect of the electrical discharge during operation. The tungsten points may be spot welded or silver soldered onto the end of the electrodes. A teaser electrode 60, being a metallic cylinder fitting the inside of the glass cylinder 51 and having one or more tips 61 extending into relatively close proximity to the electrode 54, is provided for the purpose of effecting ionization of the gas in the spark gap. This teaser electrode is believed to ionize the main gap; it reduces overshooting of the gap voltage. Without the teaser electrode, the gap may not always be broken down at desired voltage, but with the teaser electrode present, the passing of the spark across the gap at constant breakdown voltage is assured.

The interior of the gap cell is preferably filled with an inert gas such as nitrogen, argon, hydrogen, or helium at a pressure of about one atmosphere. Higher pressures may be employed and require a higher voltage to bridge the gap. Lower pressures may be employed with a corresponding reduction in voltage requirements. By so constructing the gap cell the effect of varying atmospheric pressure at different elevations above the surface of the earth is avoided.

A passage 62 is provided, between the upper end of the groove 31 and the recess 38, through which the primary of the transformer may be electrically connected with the metal plate 53 thus providing for the transmission of the electric charge which passes across the gap to the primary of the transformer. A mounting block 63 is seated in a recess in the partition 37 and serves to support the cell 50. When the cell is emplaced it is fixed in position by means of a dielectric stopper 64 that is preferably cemented in the end of the recess 38. This stopper has a central passage-way 65 to receive a metal contact member 67 electrically connected to metal base member 52

by means of a spring 68 and a contact 69. The contact block 67 may be screw threaded into the stopper 64.

A tubular condenser 70 encircles the sleeve 30 and is preferably provided with a snug fit thereabout. A passage 71 between the stopper 64 and the metal base member 52, and passage 72 in the side of the sleeve 30 receive a conductor 73 which electrically connects the condenser 70 with the metal base member 52 and the contact 67. The other side of the condenser is connected by a conductor 74 to the grounding ring 35.

The structure so assembled constitutes the second unit of the spark plug. This second unit may be telescoped over the insulator 19 until the offset 44 of the spring 43 comes in contact with the upper end of the electrode 18 and the ring 35 makes contact with wedge 20, to which it may be soldered or spot welded if desired. Over the assembled structure the shell member 16 is placed, abutting the annular flange 15 of the base member 11 and the two are butt soldered to form a protective, radio-shielding shell. The entire unit may now be, and preferably is, filled with a plastic dielectric substance such as polymerized cashew nut shell oil which fills the spaces within the shell. This material is indicated generally by the numeral 80 in one portion of the unit, but it is to be understood that it can be made to extend throughout all unfilled spaces therewithin except the interior of the cell 50.

The primary winding may be bare wire when employed in slots but is preferably insulated, for instance with plastic insulation, if wound upon a sleeve having a relatively unslotted surface. The tungsten points are spot welded or soldered, for instance by silver solder, on the ends of the gap housing. It is advisable to have large electrode surfaces at the gap, because the larger the surface the smaller is the variation in breakdown voltage, so that with electrodes of large facing area there is less overshooting. The teaser may be considered to be a condenser to ground whose function in ionizing the gap far outweighs the relatively negligible losses through its condenser action. The teaser gap is preferably smaller and preferably has a much lower breakdown voltage than the main gap. The formation of deposits on the main electrode tends to lower the breakdown voltage. The use of tungsten faces on the electrodes tends to reduce the formation of deposits. Furthermore, the wider the gap the less the deposit. Therefore, the use of the teaser permits the use of a wider gap at a satisfactory breakdown voltage. The teaser itself may be a split spring ring which is frictionally engaged with the glass wall of the cell by its own spring action. It may also be anchored thereto by the same heat treatment which anchors the metal ends of the cell to the glass. A thickness of .005 inch is adequate for the teaser.

A wiring diagram for the apparatus is shown in Fig. 2, the diagrammatic representations of which are given the numerals of the equivalent parts in Fig. 1. Thus, when a charging current, for instance of 4000 volts is broken by the distributor, the condenser discharges through the gap 55-57 to the primary 32, inducing a current in secondary 42 by principles well understood.

This structure has many advantages. It assembles within a small space upon the engine all the elements essential to the generation of a hot, high frequency spark. All the parts of the apparatus are in balance so that the tendency of unbalanced parts to introduce destructive

vibrations is lacking. Another advantage of the invention is the making of the sparking plug in telescoping units which are easily dismantled or assembled. Another advantage of the invention is in the construction of the primary and secondary coils of the transformer and in the mounting thereof. A further advantage of the invention is in the automatic making of electrical contacts between the several parts of the apparatus when the parts are assembled. Another advantage of the invention is in the separated axial alignment of the gap cell and the electrode. Yet another advantage of the invention is in the concentric arrangement of the several parts. Still another advantage is in the shell structure.

Although only one embodiment of the invention has herein been illustrated and described, it is to be expressly understood that the same is not limited thereto. Various changes may be made in the design and arrangement of the parts without departing from the spirit and scope of the invention, as will now be clear to those skilled in the art. For a definition of the limits of the invention, reference is had primarily to the appended claims.

What is claimed is:

1. A spark plug comprising a metallic cylinder, a center electrode, a transformer encircling said center electrode, and a grounding ring encircling said electrode connected with the primary and the secondary of said transformer and to the said metallic cylinder.

2. A transformer of the spark plug type comprising a mica tube having a plurality of layers, a transformer winding, and a flat spring contact having bent ends diametrically caught between the said layers and connected to said winding.

3. A spark plug comprising an electrode, an insulating sleeve telescoped over said electrode having a recess, a gap cell in said recess, transformer windings carried by said sleeve, a condenser, and means to electrically connect the parts whereby a charging current may be imposed upon the condenser and discharged across the gap to the transformer and the current induced in the transformer may be conducted to said electrode, said connecting means including a connection from the condenser to one terminal of the gap, a connection from the other terminal of the gap to the primary winding of the transformer and a connection from the secondary winding of the transformer to said electrode.

4. In combination with a high frequency spark plug comprising an insulated center electrode assembly mounted in a metallic shell, a unit including a rigid insulator having a recess in each end thereof and having telescopic relation with said assembly, a transformer having a secondary winding mounted on an insulating sleeve and interposed between said assembly and said insulator in one of said recesses and a primary wind-

ing around said insulator, resilient means supported by said sleeve for electrically connecting said secondary winding to the electrode of said assembly, a condenser around said insulator and primary winding, means connecting the low potential terminals of said condenser and said windings to said shell, a sealed spark gap mounted in the other of said recesses, means for connecting opposite terminals of said gap to the high potential terminals of said condenser and primary winding, and means whereby the condenser connected terminal of said gap may be connected to a source of electrical energy.

5. In combination with a high frequency spark plug comprising an insulated center electrode mounted in a metallic shell, a transformer unit including a rigid insulator having a recess therein and being in telescopic relation with said insulated electrode, a transformer having a secondary winding mounted on an insulating sleeve and interposed between said electrode and said insulator in said recess and a primary winding around the outside of said insulator, means for electrically connecting said secondary winding to said electrode, and a metallic ring mounted on the end of said insulator for positioning said sleeve and secondary winding in said recess, said ring having electrical connection with said shell and with the low potential ends of said windings.

6. In combination with a high frequency spark plug comprising an insulated center electrode assembly mounted in a metallic shell, a unit slidably mounted in said shell and including a rigid insulator having telescopic relation with said assembly, a transformer coil having a secondary winding within said insulator around said assembly and a primary winding around said insulator, a condenser around said insulator and primary winding, a metallic ring mounted on said insulator for positioning said secondary winding therein, said ring having electrical connection with said shell and with the low potential terminals of said windings and said condenser, means connecting the high potential end of said secondary winding to the electrode of said assembly, and a spark gap interposed between the high potential terminals of said condenser and primary winding.
